UNITED STATES PATENT OFFICE.

HARRY R. TRAPHAGEN, OF ROCKFORD, ILLINOIS, ASSIGNOR TO EMERSON-BRANTINGHAM COMPANY, OF ROCKFORD, ILLINOIS, A CORPORATION OF ILLINOIS.

TWO-ROW CULTIVATOR.

Application filed March 12, 1925. Serial No. 14,895.

This invention relates in general to cultivators and has more particular reference to two-row cultivators, although not confined to this type.

5 The primary purpose of my invention is to simplify and improve the mounting and control of the cultivator beams, as will be described more fully hereinafter.

One of the purposes of my invention is, 10 therefore, to provide a high cross-bar which connects the pivot wheels for steering and which provides a support for the cultivator beams on which they may be adjusted in pairs either to accommodate different widths 15 of rows or for proximity to the plants. With this is combined a low hitch for the cultivator beams which causes their shovels to penetrate to the proper depth and hold their position in the ground by reason of the suction produced by the incline of the shovels.

Another purpose of my invention is to provide improved mounting or support of the cultivator beams on the cross-bar through the agency of hangers, improved 25 means for adjusting the hangers and consequently the beams laterally, and improved means for applying the draft to the beams.

Still another purpose is to provide means 30 associated with the cross-bar construction for adjustment or alignment of the carrying wheels.

Other objects and attendant advantages 35 will be appreciated by those skilled in this art as the invention becomes better understood by reference to the following description when considered in connection with the accompanying drawings, in which—

Figure 1, is a top view of a two-row cultivator embodying my invention;

40 Figs. 2 and 3, are fragmentary vertical sections taken substantially on the lines 2—2 and 3—3 of Fig. 1;

Fig. 4, is a vertical section taken substantially on the line 4—4 of Fig. 1;

45 Figs. 5 and 6, are views of the cross-bar, hangers and hanger-adjusting means, viewed from the front as in Fig. 4, illustrating different adjustments;

Fig. 7, is a top view of the cross-bar and 50 hangers showing a modified form of adjusting means; and

Figs. 8 and 9, are top and side views, respectively, showing the wheel-adjusting structure.

My invention in its preferred embodiment 55 is applied to a cultivator having pivot carrying wheels 11 on which a suitable frame designated generally by 12 is supported. In this instance each wheel axle has a horizontal axle portion 13 and an upright 60 spindle portion 14 the latter of which turns in a sleeve 15 integral with a corner bracket 16 to which the rear frame cross-bar 17 and the rear ends 18 of the front frame cross-bar 19 are bolted. The wheels are mounted 65 on the axle portions 13 and are held from displacement by a sand box bracket or axle connection designated generally by 21 clamped onto the elbow portion of the axle by a U-bolt 22. To each bracket 21 is adjustably secured a forwardly and upwardly inclined side bar or steering arm 23. These side bars are pivotally attached at 24 to the ends of the cross-bar 25, thus establishing a 70 connection between the wheels for holding 75 and steering them in parallelism.

The adjustable connection between each bracket 21 and side bar 23 is for the purpose of adjusting each wheel with respect to its side bar for properly aligning the wheels. 80 Referring to Figs. 8 and 9 which apply to both side bars, it will be observed that the side bar 23 is pivotally attached at its lower rear end by means of a bolt 26 to the bracket 21 and is further secured thereto by a 85 bolt 27 which passes through a slot 28 in the cross-bar. A bolt 29 connecting the side bar at a point forward of the bolt 27 with an extension 31 on the bracket 21 and adapted to be clamped thereto by nuts 32 90 provides a means for adjusting the bracket 21 and consequently the axle and its wheel upon and about the pivot bolt 26 and with respect to the side bar 23. By reason of the connection comprising the side bars and cross-bar connecting the wheel this adjustment provides a simple and effective means for properly aligning the wheels, it being manifest that the several nuts will be tightened after the adjustment is made.

100 The cultivator may be drawn or propelled by any suitable means. At present a single draft pole is employed, although in cultivators of this kind it is also customary to use double poles. In the instant case the pole 105 33 is connected to a pivot wheel pole truck designated generally by 34 attached by rearwardly diverging side bars 35 to the main

frame. The particular pole truck structure on the cross-bar 25 and an upright tubular portion in which the upper end of the bar 56 is fixedly clamped. The lower end of this pendent bar is turned laterally to provide a horizontal portion 57 on which a beam 70

5 The cultivator beams are mounted on the cross-bar 25 which is adapted to be shifted laterally by the operation of foot levers 36 and 37 for steering the cultivator. The foot levers, pivotally mounted at 38 on seat bars 10 39 suitably fixed to the main frame, are each connected by a link 41 to a chain 42 which passes through a hole in the front frame bar 19, around a pulley 43 on said bar, and is attached to the cross-bar 25 at a point 15 centrally between its ends. In this instance the chains are connected to a bracket 44 which is secured by a bolt 45 to the cross-bar. It will be manifest from the foregoing that the operator on the seat 46 may steer 20 or guide the cultivator by operation of the foot levers 36 and 37.

This being a two-row cultivator there are four cultivator beams 47, 48, 49 and 50, commonly referred to as the left and right hand 25 pairs, as viewed by the operator. The beams may be of any suitable or preferred construction and will be equipped with suitable shovels as is customary and essential to implements of this kind. For the purpose of 30 avoiding confusion in the drawing and inasmuch as these shovels are well known in the art they have been omitted from the drawings. It will be understood however, that they should be of a type in which the 35 shovel blades are so shaped or inclined as to penetrate the ground and have a natural suction which will hold them to the working position, providing of course, that the draft is properly applied. The particular application of the draft is one of the important 40 features of my invention as will be presently noted.

Each beam, attached at its forward end to a hanger mounted on the cross-bar 25, is 45 slidable or may be otherwise shiftable lengthwise thereon for the purpose of laterally adjusting the beam. The hangers, designated generally by 51, 52, 53 and 54 for the beams 47, 48, 49 and 50 respectively, are similar 50 in construction and a description of one will suffice, similar reference numerals applying to similar parts. The hanger comprises a suitable structure mounted to slide lengthwise on the cross-bar and having a pendent 55 end terminating in a horizontal portion to which the forward end of the cultivator beam is pivotally attached and which is preferably located approximately in the horizontal plane of or coplaner with the 60 beam, that is, in the plane in which the beam is disposed when in the normal working position shown in Fig. 3. The present hanger is of two parts, namely a T-shaped bracket 55 and a pendent bar 56. The 65 bracket has a tubular cross-portion slidable

on the cross-bar 25 and an upright tubular portion in which the upper end of the bar 56 is fixedly clamped. The lower end of this pendent bar is turned laterally to provide a horizontal portion 57 on which a beam 70 connected bracket 58 is pivotally mounted. In order to hold the lower end of the hanger in a fixed location and to maintain the desired low point of draft for the beam, a push rod 58' is employed. This rod, pivotally attached at 59 to the rear frame bar 12 is inclined downwardly and forwardly and pivotally attached at 61 on a vertical axis to a collar 62 fixed as by means of a set screw 63 to the horizontal portion 57 of the hanger bar, the connection of the push rod to said bar being forward of the latter. As shown in Fig. 4 the collar 62 is interposed between the bifurcated forward end portion 64 of the bracket 58. While the push rod 75 functions to maintain the location of the low hitch or application of draft to the beam and to carry the resistance from the shovels, it will be observed that it is so mounted as to accommodate both the lateral swinging motion of the cross-bar 25 and the hangers for steering purpose and the lateral movement of the hangers upon the cross-bar for adjusting the beams with respect to the rows. In other words the 80 hangers and cross-bar assembly may be swung laterally as a unit or the hangers may be individually shifted laterally on the cross-bar, these movements being provided by reason of the pivotal connections at the front and rear ends of the push rods. The 85 weight of the hangers and beams on the cross-bar 25 is carried by the main frame through the agency of rollers 60 attached to the front frame bar 19 by suitable brackets. 90

The rear end of each cultivator beam will be supported at a determined level by any suitable means well known in this art such, for example, as by a pendent chain or link (not shown) connected to a suitable adjusting lever or equivalent device for setting the depth of the shovels.

It is desired to adjust the beams by movement of the hangers to accommodate rows of different widths and to follow variations between adjoining rows, also to adjust the beams toward and from each row to secure the desired proximity of the shovels with respect to the plants. This method of beam adjustment is particularly desired in those localities where it is customary to list the ground and plant with single row machines, as a result of which there is invariably some irregularity in the spacing of the rows. In localities where two row planters are used and the rows are parallel and equidistant apart it is only necessary to adjust the beams of each pair toward and from the plants because the operator in cultivating follows the same two rows that have been simul- 115 120 125 130

taneously planted. It is desirable for economy in the cost of production of these cultivators to provide separate controls for the two conditions, although the control for the first is applicable to both.

The first described beam control is shown in Figs. 1 to 6 inclusive. It comprises a pair of hand levers 64 and 65 pivotally mounted at 38, above-mentioned and connected to bell-crank levers 66 and 67, respectively, by means of links 68 and 69. Said bell-crank levers are coaxially mounted to turn about a trunnion 71 integral with a bracket 72 held in position on the underside of the cross-bar 25 by the bolt 45. The bell-crank lever 66 has a forwardly projecting arm 73 connected by means of links 74 and 75 to the hangers 51 and 53, respectively, or in other words to the outer beam of the left hand pair and the inner beam of the right hand pair. The other bell-crank lever 67 has a forwardly projecting arm 76 connected by links 77 and 78 to the hangers 52 and 54 respectively, that is, to the inner beam of the left hand pair and the outer beam of the right hand pair. By swinging both levers 64 and 65 rearwardly from the full line position shown the beams of each pair will be moved away from the plants as shown in dotted lines in Fig. 5 and by swinging them forwardly the beams will be moved toward the plants, this adjustment being to position or set the shovels in the desired proximity to the plants where the distance between the rows is fixed. The hangers may however, be set to different widths of rows by changing the connections of the links 74, 75, 77 and 78 with the hanger brackets, it being noted (Fig. 1) that each hanger bracket has a series of holes for this purpose. In effect, the adjustment is one for changing the effective length of the links.

Where it is desired to maintain a permanent distance between the shovels of each pair to follow irregularities in the spacing of the rows and to individually adjust each pair of beams to follow its respective row the link connections between the bell-crank levers 66 and 67 and the hangers are changed to the arrangement shown in Fig. 6. That is, the arm 73 of the bell-crank lever 66 will be connected to the hangers 51 and 52 and the arm 76 of the bell-crank lever 67 will be connected to the hangers 53 and 54. Thus, upon swinging both hand levers 64 and 65 forwardly both pairs of hangers will be moved as units toward the center of the cultivator as shown in dotted lines in Fig. 6 to accommodate a narrower spacing of the rows; or either lever might be manipulated separately to move its pair of hangers as a unit outwardly or inwardly to follow any irregularity in the spacing of the row with respect to the companion row. By reason of the provision for adjustment

between the bell-crank lever links and the hangers the latter may be set to accommodate rows of different widths.

It will be apparent from the foregoing that the double lever method of control permits of adjusting the beams toward and from the plants where the spacing of the rows is permanent, as shown in Fig. 5, or of individually adjusting each pair of beams as a unit to follow its row which may vary in distance from the adjoining row, as shown in Fig. 6. A control of this kind is therefore, adapted for the conditions in both localities above-mentioned.

In Fig. 7, I have shown a modified form of beam control employing only a single hand lever, this being adapted for cultivators intended to be used only where the planting has been done with double row planters. In this case the cultivator follows the two rows planted by the planter and the rows are consequently equidistant apart at all points. In this form the single lever 79 is connected by means of a link 81 to a lever designated generally by 82 pivotally supported by the same means and in the same location as the levers 66 and 67. The lever 82 has a forwardly extending arm 83 connected by links 84 and 85 to the hangers 52 and 54, respectively, and a rearwardly extending arm 86 connected by links 87 and 88 to the hangers 51 and 53 respectively. It will be evident that the beam adjustment in this case will be similar to that shown in Fig. 5 except that it is accompanied by operation of a single hand lever instead of two such levers.

It is believed that the foregoing conveys a clear understanding of my invention especially with regard to the various adjustments and controls of the cultivator beams. Attention is, however, directed to the simplicity of the construction whereby said various adjustments are obtained in combination with a pivot wheel dirigible cultivator, and in further combination with a high cross-bar and low beam hitch. It will be manifest, of course, that the steering is accomplished without disturbing the setting or adjustment of the beam hangers on the cross-bar. The low beam hitch is especially advantageous in that no extraneous means or devices are necessary to hold the shovels in the ground, but instead the low draft from the lower ends 57 of the hangers combined with the ordinary suction of the shovels holds the latter to working depth. Another advantage of the construction is that the desired plant clearance is provided by reason of the high cross-bar and at the same time provision is made for either individual or unit adjustment of the beams. It will be particularly noted that with this arrangement the cultivator beams have a low point of draft. It will be manifest to those skilled

in this art that this combination has distinct advantages over those cultivators in which the beams are attached at low points to single piece arches or the equivalent, and are consequently not laterally adjustable upon the arches, or in which the beams are attached at their forward ends to comparatively high cross-bars or the equivalent and therefore, have a correspondingly high hitch.

It is believed that the foregoing conveys a clear understanding of the objects prefaced above and although I have illustrated several embodiments of the beam control it should be understood that in putting my invention into practice various changes might be made in details of construction, and the substitution of equivalent parts and devices without departing from the spirit and scope of the invention as expressed in the appended claims, in which—

I claim:

1. A cultivator, comprising, a frame, pivot carrying wheels therefor having steering arms, a cross-bar connecting the steering arms of said wheels to swing the same, cultivator beams, a hanger for each beam mounted at its upper end on the cross-bar to slide thereon and attached at its lower end to the forward end of the beam, a push rod for each beam pivotally connected on a vertical axis at its rear end to the frame and inclined forwardly and downwardly and pivotally connected also on a vertical axis at its forward end with the lower end of the hanger, the said push rod swinging on approximately the same radius as said steering arms and having its fore and aft pivots substantially aligned in a vertical plane with the fore and aft ends of said arms, and control means for sliding the hangers on the cross-bar to laterally adjust the beams.

2. A cultivator comprising, a frame, pivot carrying wheels therefor having steering arms, means connecting the arms of said wheels for steering, including a cross-bar located at a comparatively high position at the front of the frame, cultivator beams, a hanger for each beam mounted at its upper end on the cross-bar and pivotally attached at its lower end to the forward end of its beam on a horizontal axis substantially coplanar with the beam in its normal working position, and a push rod for each hanger pivotally connected on a vertical axis at its rear end to the frame and inclined forwardly and downwardly and pivotally connected on a vertical axis at its forward end with the lower end of the hanger, the said push rods swinging on approximately the same radius as said steering arms and having their fore and aft pivots substantially aligned in a vertical plane with the fore and aft ends of

said arms whereby to maintain the location of the beam hitch and to resist the thrust of the cultivator shovels.

3. In a two-row cultivator, the combination of a frame, two pair of shovel beams at opposite sides of the frame, a pair of levers arranged between the pairs of beams for shifting said beams laterally, a long and a short link connected with each lever and extending therefrom for connection with parts shiftable with said beams, said links being arranged to extend in opposite directions from said levers in one state of adjustment to operate one beam of each set, and one of said links being arranged to be reversed to extend in the same direction as its companion so that the two links in the new state of adjustment operate both the beams of one set, said levers being arranged when the short and the long links connected therewith are extended in opposite directions to shift the beams of each set closer together or farther apart and being arranged when the short and long links connected therewith are extended in the same direction to shift the sets of beams toward and away from one another.

4. In a cultivator as set forth in claim 3, the provision of connections between said links and said shovel beams for varying the effective length of the links whereby to vary the spacing of the beams in a set or to vary the spacing of the sets of beams in the two possible arrangements of said links.

5. In a cultivator, the combination of a frame having carrying wheels, a plurality of sets of beams drawn with said frame, a cross member, parts slideable laterally of the frame on said cross member for shifting said beams, an operating member at an intermediate position with respect to said cross member and short and long links extending in opposite directions from said operating member having connection with said slideable parts, the long or short links being arranged to be reversed to extend in the same direction as companion links operated therewith and to have connection with slideable parts toward the opposite end of the cross member whereby the beams of each pair may be shifted toward and from each other or the sets of beams may be shifted toward and from each other substantially as described.

6. In a cultivator as set forth in claim 5, the provision of adjustable connections for the one end of said links to determine different fixed lengths of connections between the shovel beams and said operating member, the said connections determining in one case a different initial spacing of the beams in a set or in the other case a different spacing of the sets of beams substantially as described.

HARRY R. TRAPHAGEN.
